UNITED STATES PATENT OFFICE.

ENOCH DEMSKY AND CHARLES REDECKER, OF ST. LOUIS, MISSOURI,
ASSIGNORS TO MOON BROTHERS CARRIAGE COMPANY, OF ST.
LOUIS, MISSOURI, A CORPORATION OF MISSOURI.

VEHICLE-BODY.

No. 826,491.

Specification of Letters Patent.

Patented July 17, 1906.

Application filed July 3, 1905. Serial No. 268,194.

To all whom it may concern:

Be it known that we, ENOCH DEMSKY and CHARLES REDECKER, citizens of the United States, residing at St. Louis, Missouri, have 5 invented a new and useful Vehicle-Body, of which the following is a specification.

This invention relates to the construction of vehicle-bodies; and it consists of various improvements which are fully shown in the 10 accompanying drawings, which form part of this specification.

Previous efforts of manufacturers to produce a vehicle-body which will withstand all 15 variations of weather conditions and maintain a smooth and unbroken surface have, so far as known, met with failure. The panels have usually been fastened in place by nails or screws or similar fastening devices, which pass through the panels, the heads of such 20 devices usually resting in countersinks in the panels and being covered over flush with the surface of the panel by plugs of various kinds. Such expedients are ineffective for permanent smoothness, and, as is well known, the rigors 25 of climatic variations have a telling effect thereon, resulting eventually in a perceptible line of cleavage or demarcation between the panel and the plug, and finally the latter may drop out. In any event the line of demarcation is unsightly and results in a permanent defacement which destroys the artistic finish of the vehicle-body.

Other expedients have been resorted to—such, for instance, as dovetailing the panels 35 to the posts or uprights; but perfect fit is difficult to secure, and especially so as the grooves and tongues for each panel must all be parallel in order to render possible the positioning of the panels. Therefore, in view of 40 the well-known fact that most vehicle-bodies flare outward at the top and that the posts or uprights must also lean outward, it is in such cases impossible to make the dovetails on the posts or uprights parallel, and the inadequacy of this method of fastening the panels 45 is evident.

Staples or bent metal wedges are impracticable for various reasons, prominent among which is the fact that they could only bind 50 the edges of the panel and the middle portion would warp. To avoid all the aforesaid difficulties and to produce a strong, durable, and

adequate fastening device, one that can be used on all shapes of vehicle-bodies, whether flaring or not, and that efficiently binds the 55 panel at all necessary places without in any manner defacing the exterior surface of the panels, is the object of our present invention.

In the accompanying drawings, wherein our invention is illustrated, Figure 1 is a perspective view of a vehicle-body partially assembled, showing the application of our invention. Fig. 2 is a vertical section of a panel and post, showing the fastening attachment in place. Fig. 3 is a cross-section of a 60 panel and sill with the fastening device there-in. Fig. 4 is a bottom view of a vehicle-body constructed in accordance with our invention. Figs. 5, 6, and 7 are views illustrative of the various stages or steps passed through in the 65 practice of our invention.

The general principles of our invention are illustrated in Figs. 5, 6, and 7, wherein are shown two objects in the various stages from their relation as separate pieces until they 70 are united and fastened together. The fastening member employed consists of a long piece of thin metal 1, provided on its edges with lateral parallel projections 2, the preferred form being one in which the projections 75 extend both ways, thereby forming an I-beam, which form is shown in the various figures of the drawings. The piece 3, of wood, and the piece 4, also of wood, Fig. 5, are to be fastened together. In said piece 3 80 a saw kerf or groove 5 is formed, and a corresponding kerf or groove 6 is formed in the piece 4, the kerfs or grooves being of substantially equal depth and in width equal to or slightly less than the thickness of the web of beam 1 and their combined depth equal to 85 the depth of the said beam 1. A coat of glue (showing at 7 in Figs. 6 and 7) is then placed on one of the pieces, and they are then brought together so that the two kerfs or grooves 5 and 6 register, thereby forming a single continuous passage-way as far as they run. The pieces are then ready for the application of 90 the fastening member comprising the flanged beam 1. Said beam is thereupon driven into the passage-way formed by said kerfs or 95 grooves, and the flanges 2 embed themselves into the sides of said passage-way, as clearly shown in Fig. 7, thereby firmly uniting the 100

two pieces without in the least defacing the exterior surface of the outer piece 4, which is the object to be attained.

As applied to vehicle-bodies our invention, 5 as illustrated in Figs. 1 to 4, inclusive, consists in the formation of registering kerfs or grooves in the uprights and, if desired, in the sill and the formation of registering kerfs or grooves in the panels, gluing the panels onto 10 the uprights and sills and driving the fastening devices into the passage-ways formed by the said kerfs or grooves.

As shown, the numeral 8 indicates the sill 15 of the frame. 9 indicates the corner posts or uprights, and 10 the uprights which are under the seat, the upper ends of the last-named uprights at each side being joined by a brace 11. In the outer faces of the corner-uprights 20 are formed kerfs or grooves 12, which may or may not extend throughout the length thereof, and similar kerfs or grooves 13 are formed 25 in the outer faces of the uprights 10, which are longer than those at the corners. At the ends of the panels 15 kerfs or grooves 16 are formed in such position that they register 30 with those in the corner-uprights when the panels are glued in position. Likewise kerfs or grooves 17 are formed in the inner faces of the side panels across both pieces 15 and 15^a, 35 constituting each panel, in such position that they register with the kerfs or grooves 13 in the uprights 10. At intervals along the sills 8 kerfs or grooves 18 may be formed; but these should not extend entirely across the 40 outer face of the sills, but should leave the upper surface of the sills intact, so that moisture cannot enter. Similar registering kerfs 19 are formed in the panels. Kerfs 20 are formed in the braces 11 and similar registering kerfs 21 in the upper portions 15^a of the panels.

After the various kerfs or grooves have been formed glue is placed upon the frame or upon the panels, and the panels are then 45 placed in position. If desired or found advantageous, the panels can be clamped and so held firmly in position until the entire body is finished or as long as necessary. While so held long fastening devices 31, 50 preferably in I-beam form, as described, are driven into the passages formed by the kerfs 12 and 16 at the ends of the panels and also into the passages formed by the kerfs 13 and 17 at the center. The passage-ways, as 55 heretofore described, should be smaller than the I-beams, so that they will bind firmly therein. The flanges 32 embed themselves in the wood. It is preferred that the fastening devices in the uprights shall extend the 60 full length thereof and also the full width of the panels, so that the latter will be firmly and securely held against warping; but, as indicated in dotted lines in Fig. 2, a shorter fastener may be driven into each end of the 65 passage-way, and if too much space be not

left such arrangement will suffice. By this system of fastening the panels it is apparent that the separate upper portions 15^a will be more firmly, securely, and fixedly held in place on the main portion 15 than could possibly be by employing screws or nails or the like or even if the panels were dovetailed onto the uprights.

In the passages 18 19 short fasteners are driven, as indicated at 22 in Fig. 3. These 75 do not extend all the way through the sills, but leave the upper surface of the sill unbroken, so that the panels fit flush against the upper edges of the sills all along, thereby forming a more perfect and an unbroken 80 joint. In the passages 20 21 fasteners are also driven, as shown at 23 in Fig. 1, and by said fasteners 22 and 23 the edges of the side panels will be securely held. The lower edges of the end panels are also held by fasteners 22, as shown in Fig. 4. Fasteners of this character are vastly superior to nails, screws, or plugs, because there is no defacement of the finished exterior of the panels and for the further reason that a continuous 90 bond is formed as far as the I-beams extend, and they may be made to extend entirely across the panels transversely of the grain thereof, so that warping is absolutely impossible. No shrinkage or loosening of the 95 panels occurs, as so frequently happens when simple dovetailing of the panels onto the uprights is the fastening method employed. All portions of the panels will be held with 100 equal rigidity against the uprights, and the lower edges are firmly bound by the short fasteners there. Moreover, in the present system of screwing the panels onto the frames several days are required in which to 105 finish a vehicle-body; but by this method of fastening the panels the entire body can be completed within a few hours, thereby hastening the manufacture and enabling the manufacturer to produce a superior article 110 in less time and at reduced cost.

We are aware that there may be variations or modifications from the details herein described without in the least departing from the spirit and scope of the invention, and we do not wish to be understood as restricting 115 ourselves to exact details; but,

Having described the invention, what we do claim, and desire to secure by Letters Patent, is—

1. In vehicle-body construction, a post and panel each provided with a registering kerf and a flanged locking member driven into said registering kerfs and whose flanges are embedded in the sides of the kerfs and whose web portion substantially fills the 125 kerfs, substantially as described.

2. In vehicle-body construction, a post and a panel each provided with a registering kerf, an adhesive substance between said parts, and a flanged locking member driven 130

into said registering kerfs when said adhesive substance is pliable, the flanges of said locking member being embedded into both sides and near the bottoms of each kerf, substantially as described.

3. In a vehicle-body construction, a post and a panel, each provided with a registering kerf, and a flanged locking member I-shaped in cross-section whose depth is substantially equal to the combined depths of said registering kerfs, said locking member being driven into the registering kerfs, the

flanges thereof forming their own seats and being embedded into both sides and at the bottom of each kerf; substantially as described. 15

In testimony whereof we have signed our names to this specification in the presence of two subscribing witnesses.
